COMBINED CHAIR AND RACK

David Chapman, Chicago, Ill., assignor to Brunswick Corporation, a corporation of Delaware

Filed Feb. 16, 1959, Ser. No. 54,629

Term of patent 14 years

(Cl. D33—11)

Fig. 1 is a front perspective view of a combined chair and rack showing my new design;

Fig. 2 is a front elevational view thereof;

Fig. 3 is a side elevational view looking toward the left-hand side of Fig. 2; and

Fig. 4 is a bottom plan view of the rack portion.

The dominant features of my design are shown in full lines on the drawing.

I claim:

The ornamental design for a combined chair and rack, as shown and described.
